[57] ABSTRACT

A plurality of electrical contacts other than the first and last one each connected to any one of a second plurality of bus bars. Each bar is connected through a corresponding lamp to one end of a common switch. The other end of the switch is connected to one side of a power supply. The other side of the power supply is connected to a contact arm manually movable to any one of the contacts. The user plays against a built in program to win or lose in accordance with specified rules.

FIG. 1

FIG. 2

FIG. 3

FIG. 4

INVENTOR.
JOHN RUGGIERO

COMPUTER GAME

SUMMARY OF THE INVENTION

My invention employs special game apparatus. This apparatus employs a plurality of electrical contacts as for example, 25, disposed in spaced apart position along a semicircle. The first contact represents start position; the last contact represents end or winning position. A movable contact arm can be manually swung about a pivot point to connect to any one of the contacts. The arm is connected to one terminal of a power supply. The other supply terminal is connected to one side of a push button switch. The other side of the switch is connected in common to one side of each of a plurality, for example, four lamps. Each lamp has a different digit as for example digits one, two, three and four, associated therewith. The other side of each lamp is connected to a corresponding bus bar. Each contact other than the start contact and end contact is connected to a bus bar, the particular connection being chosen in accordance with a preselected pattern designated as a program.

With the arm positioned at start, the user advances the arm one, two, three or four contacts from start toward end position. He then presses the button, and one of the lamps then lights in accordance with the program. This lamp then indicates the number of contacts, one, two, three or four by which the arm is to be advanced toward end position. This programmed move is deemed to be a "computer" move. The process continues as above with the player and program taking turns. If the last move required to place the arm in end position has been made by the player, the player is said to have won. If the last move has been made in accordance with the program, the player has lost and the "computer" is said to have won.

BRIEF DESCRIPTION OF THE DRAWINGS

In the drawings:

FIG. 1 is a perspective view of my invention; and FIGS. 2, 3 and 4 are circuit diagrams illustrating different player and computer moves.

DETAILED DESCRIPTION OF PREFERRED EMBODIMENTS

Referring now to FIGS. 1-4, a hollow case 100 contains four lamps 120, 140, 160, and 180 designated as digits one, two, three, and four respectively. It also contains push button switch 200 and a battery 220 as well as a rotary switch having a pivotable switch arm 240 pivotable about one end and adapted to contact at its other end any one of 25 different contacts disposed in spaced relationship in a semicircle. The first contact labelled S for start. The last contact numbered 24 is the end or winning position. The remaining contacts are numbered in sequence from 1 through 24.

The arm 240 is connected in series with the battery to one side of button switch 200. The other side of switch 200 is connected in common to one side of each of lamps 120, 140, 160 and 180. The other side of each of these lamps is connected to a corresponding one of

bus bars 28, 30, 32 and 34. Contacts 2, 3, 7, 11, 12, 18 and 19 are connected via bar 28 to lamp 120 whereby when the arm 240 is connected to any one of these contacts and button 200 is depressed, lamp 120 lights. Contacts 6, 10, 14, and 17 are connected via bar 30 to lamp 140 whereby when arm 240 is connected to any one of these contacts and button 200 is depressed, lamp 140 lights. Contacts 1, 5, 9, 13, and 16 are connected via bar 32 to lamp 160 whereby when arm 240 is connected to any one of these contacts, and button 200 is depressed, lamp 160 lights. The remaining contacts, other than 5 and 24, are connected to lamp 180 via bar 34 whereby when arm 240 is connected to any one of these contacts and button 200 is depressed, lamp 180 lights.

FIG. 2 shows a player move to contact 3 followed by a computer move to contact 4. FIG. 3 shows a player move to contact 5 followed by a computer move to contact 8. FIG. 4 shows a player move to contact 10 followed by a computer move to contact 12.

Obviously the program can be changed by changing connections between contacts and bus bars.

While I have described my invention with particular reference to the drawings, such is not to be considered as limiting its actual scope.

Having thus described this invention, what is asserted as new is:

1. Game apparatus comprising:
a push button switch;
a source of power;
a rotary switch having a switch arm movable to any one of a first plurality of contacts arranged in spaced consecutive position from first to last;
a second plurality of numbered lamps
a like second plurality of bus bars, each bar being coupled to one side of a corresponding lamp;
means coupling each contact other than the first and last to one of said bars;
means connecting the other side of each of said lamps to one side of the button switch; and
means connecting said arm through said source to the other side of the button switch, whereby the player and the apparatus have alternate moves within prescribed limits against each other with the player in his turn rotating the switch arm a desired number of contacts away from the first contact, the player then pushing the button to activate a lamp to learn by the thus indicated number the number of moves intended to be made by the apparatus, the player then rotating the switch arm the thus indicated number of contacts to complete the turn of the apparatus, and repeating said sequence until the player or the apparatus, in their respective turns, cause the switch arm to be moved to the last of said contacts to thus win the game.

2. A game as set forth in claim 1 wherein said first plurality is equal to 25.

3. A game as set forth in claim 2 wherein the second plurality is four and the lamps are numbered 1 through 4.

4. A game as set forth in claim 3 wherein the source is a battery.
